BY *George W. Miller*

UNITED STATES PATENT OFFICE

GEORGE W. MILLER, OF WICHITA, KANSAS

SUN AND RAIN SHIELD

Application filed September 1, 1927. Serial No. 216,987.

My invention relates to a protecting device or shield for the purpose of shielding the occupants from sun or rain by being placed at the top of the auto window, inside of the 5 auto so as to be extended outward and downward as desired.

The object of my invention is to provide a sun and rain shield that will not detract from the appearance of the automobile, and 10 in beauty and appearance is in keeping with the rest of the auto.

Another object of my invention is to provide a sun and rain shield in permanent housing on the inside of the window of the auto 15 when in an inactive position.

Another object of my invention is to provide a sun and rain shield which can be extended in active position with one hand while driving.

20 Another object of my invention is to provide a sun and rain shield that automatically locks and stays in position without any adjustments.

With the above and other objects in view 25 my invention further includes the following novel features and detail of construction, to be hereinafter more fully described and illustrated in the accompanying drawings, and pointed out in the appended claims.

30 In the drawings Figure 1 is an isometric view of an opening with invention installed therein.

Figure 2 is a detailed side view of the supporting ratchet, etc.

35 Figure 3 is an edge view of Figure 2.

Figure 4 is a detailed view of ratchet wheel.

Figure 5 is a detailed view of ratchet cover.

40 At 1 is shown the jam of the opening on which the bracket 2 is mounted and held in position thereon by means of screws which are passed through the openings 6 and 7, and screwed into the jam 1, and between the bracket 2 and 2 is placed a spring actuated 45 roller 4 on which is mounted the curtain 3.

On the lower end of the bracket is a ratchet of which 9 is the ratchet wheel firmly secured to bracket 2. 5 is a ratchet arm with lug on circuit end to engage teeth of the ratchet 50 wheel to hold shield in three determined po-

sitions. Arm 5 rotates on the ratchet wheel 9. Enough space is allowed to give lug clearance so as to pass over ratchet teeth. The spring in the shield roller urges the lug into the ratchet teeth, the other end of the arm 55 has a triangular turn and engages in the end of the curtain rod 10. 8 is a covering of the ratchet wheel. 11 is a screw to hold the covering on. 10 is the curtain rod attached to the free end of curtain. 3, being hollow 60 the ratchet arm 5 enters and is securely held.

The operation of this apparatus is as follows: By taking hold of the rod 10 and pushing outward and downward to any of the 65 positions determined by the ratchet wheel on the member 9, gravity and the spring actuated curtain roller 4 will cause a lug on the ratchet arm to engage the ratchet teeth in member 9, thereby holding shield in active positions.

Such modifications may be made as lie 70 within the scope of the appended claims.

Having described my invention, what I claim as new and desire to secure by Letters Patent is:

1. A sun and rain shield including a frame having side members, one side member having its end extended forwardly and spaced from the side member to define an elongated space, a bracket associated with one side member of the frame, a pin extending from said bracket and disposed in the space of the side member associated therewith to adjustably support the frame, and means for holding the frame in a position of adjustment. 80

2. A sun and rain shield including an adjustable frame, said frame having side members, one of the side members having a portion of its length adjacent to its end, bent upon itself defining a slot, a tooth extending laterally from the extremity of said side member, a bracket having pins extended into the slots to pivotally support the frame, said bracket having a tooth formed on its edge to be engaged by the teeth of the frame to 85 adjustably support the frame.

3. A sun and rain shield including an adjustable frame having side members, one of the side members having a portion of its length adjacent to its end, bent upon itself 90

100

defining a slot, a tooth extending laterally from the extremity of said side member, said side members operatively connected by a tube cross member for width adjustment.

5 4. A sun and rain shield including an adjustable frame having a pair of side members, each of the side members having a portion of its length adjacent to its end, bent upon itself defining a slot, a tooth extending laterally from the extremity of said side members, said side members operatively connected by a tube cross member for width adjustment.

10 5. A sun and rain shield including an adjustable frame, said frame having side members, one of the side members having a portion of its length adjacent to its end, bent upon itself defining a slot, a tooth extending laterally from the extremity of said side members, a bracket having a tooth formed on its edge to be engaged by the teeth of frame, said bracket having pins extending into the slots to pivotally support and position frame to be urged to engage the tooth of the bracket by 20 the tension of the spring actuated shade connected to frame.

15 6. A sun and rain shield including an adjustable frame, said frame having a pair of side members, each of the side members having a portion of its length adjacent to its end, bent upon itself defining a slot, a tooth extending laterally from the extremity of said side members, a pair of brackets, each having teeth formed on its edge to be engaged by 30 the teeth of the frame, said pair of brackets each having pins extended into the slots to pivotally support and position said frame to be urged into engagement by the tension of the spring actuated shade connected to frame.

20 7. A sun and rain shield including an adjustable frame, said frame having a pair of side members, each of the said side members having a portion of its length adjacent to its end bent upon itself defining a slot, a tooth 35 extending laterally from the extremity of said side members, a pair of brackets each having teeth formed on its edge to be engaged by the teeth of the frame, a spring actuated shade operatively connected to the upper end of said brackets and connected to the frame, said brackets having pins extended to the frame to be urged into engagement by the tension of the spring actuated shade.

50 In testimony whereof I affix my signature.
55 GEORGE W. MILLER.
